US0D1036887S

(12) **United States Design Patent** (10) **Patent No.:** **US D1,036,887 S**
(45) **Date of Patent:** **** Jul. 30, 2024**

(54) **STAND FOR A SHAVING RAZOR**

(71) Applicant: **The Gillette Company LLC**, Boston, MA (US)

(72) Inventors: **Christopher Ramm**, Attleboro, MA (US); **Robert Harold Johnson**, Boston, MA (US)

(73) Assignee: **The Gillette Company LLC**, Boston, MA (US)

(**) Term: **15 Years**

(21) Appl. No.: **29/918,689**

(22) Filed: **Nov. 29, 2023**

Related U.S. Application Data

(62) Division of application No. 29/767,496, filed on Jan. 22, 2021, now Pat. No. Des. 1,015,012, which is a division of application No. 29/660,084, filed on Aug. 17, 2018, now Pat. No. Des. 916,495.

(57) **CLAIM**

The ornamental design for a stand for a shaving razor, as shown and described.

DESCRIPTION

FIG. 1 is a front perspective view of a stand for a shaving razor showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown illustrate portions of the stand for a shaving razor and form no part of the claimed design.

1 Claim, 7 Drawing Sheets
